(57) **CLAIM**

The ornamental design for a digital camera, as shown and described.

DESCRIPTION

FIG. 1 is a front, right and top perspective view of a digital camera, showing my new design;

FIG. 2 is a rear, left and bottom perspective view thereof;

FIG. 3 is a front, right and top perspective view thereof, shown with the digital camera in an open configuration;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof; and,

FIG. 10 is an enlarged view of portion 10 shown in FIG. 1. The broken lines shown in the drawings illustrate portions of the digital camera that form no part of the claimed design. The dot-dash broken lines indicating an enlargement portion of the design forms no part of the claimed design.
